CULVERT CLEANER AND POST HOLE DIGGER

William Minier, Milo Township, Bureau County,
III.

Application May 24, 1938, Serial No. 209,855

3 Claims. (Cl. 294—53)

This invention relates to a culvert cleaner and post-hole digger, and it consists in the constructions, arrangements and combinations herein described and claimed.

5 It is an object of the invention to provide a tool readily adapted to cleaning of culverts and in which opposed sides of a culvert may be simultaneously scraped to loosen material therefrom, and in which the scraper blades cooperate 10 in a manner for removing the loosened material.

It is also an object of the invention to provide 15 a device of the character described in which one of the cutting or scraper blades is swingably mounted with respect to a fixed blade so as to provide means for retaining loosened material, and to also provide means for actuating the swinging blade for discharge of material therefrom.

It is a still further object of the invention to 20 provide a tool of the type described which may be also employed in the digging of post-holes.

Additional objects of the invention will be apparent from the following description and accompanying drawing, wherein

25 Figure 1 is a side elevation of the tool.

Figure 2 is a top plan view thereof.

In carrying out the invention, I make use of a shovel-like member 10 having a ferrule 11 for securing of a handle 12. The handle 12 is 30 preferably of substantial length in order that the shovel may be advanced well within a culvert or post-hole, as the case may be.

At a suitable point upon the upper forward end of the ferrule 11 there is provided a pair of 35 upstanding ears 13, the upper end being apertured to receive a pivot pin 14 which rockably mounts a lever 15, the pivot of which is intermediate its length. The ends of the lever are apertured and in respective apertures there is 40 pivoted a link 16 and a link 17. The link 16 has its other end pivotally connected in an ear 18 of a blade 19 swingably mounted in ears 20 of the spade 10. The ears 20 are preferably formed integrally with the spade, positioned at opposite 45 longitudinal edges thereof.

The blade 19 is of semi-circular formation having a cutting edge 19' and parallel arm portions 21, apertured and aligned with apertures of the ears 20 for reception of a pivot pin 22.

50 A tension spring 23 is connected between the levers 15 and 16, normally holding the blade 19 in an open position, as shown in Figure 1.

The link 17 is reduced and threaded, as at 24, for adjustable connection with a yoke 25 pivotally connected to a link 26 intermediate its length.

One end of the link 26 is pivotally mounted upon an upstanding ear 27 of the ferrule 11, the other end of the link 26 pivotally mounting a clevis 28, the outer end of which revolubly supports a pulley 29.

5 An operating cable 30 is trained about the pulley 29, one end being secured to the handle 12 as at 31, at a point approximately medially of the handle, the other end of the cable being fixed in an eye 32 at the forward end of the handle. 10

In use, whether employed as a culvert cleaner or post-hole digger, the parts will be in the position shown in full lines in Figure 1. In this position, the shovel 10 and blade 19 will be in position to scrape the bottom and top sides of a culvert or the opposite sides of a post hole. Thus, by advancing the tool, the spade and blade will loosen material and when it is desired to remove the material thus loosened, the shovel 10 is advanced to scoop up the material. The cable 30 is 20 now drawn upon in the direction of the arrow, the parts associated with the blade 19 then moving to the position shown by dotted lines, tensioning the spring 23. In this position of the blade 19 the material will be effectively retained 25 upon the shovel 10. When it is desired to discharge the material the cable 30 is released and the spring 23 moves the blade and associated levers and links to their full line positions.

While I have shown and described a preferred 30 construction, this is by way of illustration only, and I consider as my own, all such modifications in structure as fairly fall within the scope of the appended claims.

I claim:

1. In a device of the character described, a shovel having a handle, a pair of upstanding ears on the handle, an ear on the longitudinal edges of the shovel, a semi-circular blade swingably mounted between the ears of the shovel, said 40 blade normally extending at right angles to the shovel, with its cutting edge presented in the same plane as the point of the shovel, a lever pivotally connected to a rear portion of the blade, a lever pivotally mounted intermediate its length between the ears of the handle one end having pivotal connection with the first named lever, a further ear on the handle, a link pivoted thereto, an adjustable lever pivoted to the link intermediate its length, said adjustable lever 45 having pivotal connection with the other end of the second named lever, and cable means for imparting motion to the link.

2. The structure of claim 1 in which spring means are connected between certain levers for 50 55

returning the blade to operative position after actuation by the cable.

3. In a device of the character described, a shovel having a handle, a pair of upstanding ears on the handle, an ear on the longitudinal edges of the shovel, a semi-circular blade swingably mounted between the ears of the shovel, said blade normally extending at right angles to the shovel, with its cutting edge presented in the same plane as the point of the shovel, a lever pivotally connected to a rear portion of the blade, a lever pivotally mounted intermediate its length between the ears of the handle one end having

pivotal connection with the first named lever, a further ear on the handle, a link pivoted thereto, an adjustable lever pivoted to the link intermediate its length, said adjustable lever having pivotal connection with the other end of the second named lever, a pulley carried by the free end of the link, a cable trained about the pulley, one end of the cable being anchored adjacent the medial portion of the handle, the other end being anchored adjacent the end of the handle, and a 5 helical spring connected between the first and second named levers. 10

WILLIAM MINIER.
